SANDBLAST GUN BODY

Stewart Ives Ashworth, Vale, Guernsey, Channel Islands,
assignor to Abrasive International Limited, Henley-in-
Arden, England

Filed Apr. 21, 1975, Ser. No. 570,132

Claims priority, application Great Britain Jan. 14, 1975

Term of patent 14 years

Int. Cl. D15—09

U.S. Cl. D15—126

FIG. 1 is a side elevation of a sandblast gun body;
FIG. 2 is a plan view of a sandblast gun body;
FIG. 3 is an end view of a sandblast gun body in the
direction of the arrow 3 in FIG. 1; and
FIG. 4 is an end view of a sandblast gun body in the di-
rection of the arrow 4 in FIG. 1.

I claim:

The ornamental design for a sandblast gun body, as
shown.
